UNITED STATES PATENT OFFICE.

CURT STILLE, OF ZEHLENDORF-WEST, NEAR BERLIN, GERMANY.

ELECTRICAL CONNECTION FOR ELECTRIC RELAYS.

1,160,547.

Specification of Letters Patent.

Patented Nov. 16, 1915.

Application filed March 21, 1914. Serial No. 826,321.

To all whom it may concern:

Be it known that I, CURT STILLE, doctor of philosophy, of Zehlendorf-West, near Berlin, Germany, a subject of the King of Prussia, and whose post-office address is 4/5 Bülowstrasse, Zehlendorf-West, near Berlin, Kingdom of Prussia, German Empire, have invented a new and useful Improved Electrical Connection for Electric Relays, of which the following is a specification.

Electric relays have already been proposed in which two oppositely rotating coils compress or release a microphonic contact, according to whether the current is directed in the one or the other direction. A special construction of such relays has also been suggested in which the microphone contacts are not located between the two coils, but on the contrary are pressed by arms secured on the coils, while the microphone themselves are fixed. According to the present invention an improved arrangement of electrical connection is provided for such relays by which sounds, especially sibilants, are repeated with greater clearness.

In the improved arrangement the coils are preferably of different resistances, the one for example having 200, the other 10 ohms resistance, and each coil carries an arm for each microphone.

In the accompanying drawing Figure 1 is a diagrammatic view of a relay and the microphones employed in carrying out the invention. Fig. 2 is a diagram of the electrical connections of the elements of the invention, the coils being illustrated in this figure separated from each other for greater clearness.

With reference to Fig. 1, P and S are the primary and secondary coils of the relay suspended by means of hooks C₁ C₂ C₁¹ C₂¹ and threads or strings E₁ E₂ E₃ E₄ attached to the coils. Mounted on the primary coil are four arms F₁ F₂ F₃ F₄ with corresponding contact pieces D₁ D₂ D₃ D₄ pressing against corresponding contact pieces on the microphones A₁ A₂ A₃ A₄, corresponding arms and contact pieces being also provided for the secondary coil S. Electrical conductors L₁ L₂ and M₁ M₂ are attached to the ends of the coils P and S.

The electric connections are shown in Fig. 2; only a single microphone A is shown, while as mentioned before in practice, on account of symmetry, four such microphones are preferably employed.

The primary coil P is secured directly to the conductor, that is at L¹ and L² as shown in Fig. 1. From a secondary coil S two conductors M¹, M² lead, and are connected to the hearing or receiver apparatus, a telephone H for example. The conductors M¹ and M² are branched and the battery B and the microphone A are connected in parallel with the receiver H. The microphone is subjected to variations in pressure from the two contacts D¹, d¹ carried by the two coils P and S.

The operation of the apparatus is as follows:—In the receiving apparatus H are first of all effective those currents which are directly produced by the coil S. Superposed on these currents, however, are the currents from the battery B, which as a result of the mechanical forces exercised by the coils P and S become influenced in their intensity by the resistance of the microphone A. For insuring effectual working, conformity in the phase of these two currents, which obviously follow the same oscillations, should apparently be considered. It appears, however, that even if such conformity in phase is not present, there is a favorable influence for repeating the vibrations, as both apparatus have the tendency, in a similar manner to two alternating current machines connected in parallel, of synchronizing, that is bringing about an elimination of the difference in phase.

What I do claim as my invention, and desire to secure by Letters Patent of the United States, is:

1. A microphone relay device comprising a microphone, suspended primary and secondary coils movable against each other, the microphone being subjected to pressure from said coils, a circuit including said secondary coil, a battery and said microphone, and a hearing device connected across to said circuit.

2. A microphone relay device comprising a microphone and suspended primary and secondary coils rotatable against each other, the microphone being subjected to pressure from said coils, a circuit including said secondary coil, a battery and said microphone, and a hearing device connected across to said circuit.

3. In a microphone relay, a primary coil, a secondary coil, arms carried by said coils, a microphone subjected to pressure from said

arms and a receiver to which said microphone and secondary coil are both connected.

4. In a microphone relay, a primary coil, 5 a secondary coil, a microphone influenced by the relative movement of said coils and a telephone receiver to which said microphone and secondary coil are both connected.

5. A microphone relay device comprising 10 a microphone, suspended primary and secondary coils movable against each other, and arms carried by said coils; the microphone being subjected to pressure from said coils, a circuit including said secondary coil, a battery and said microphone, and a hearing device connected across to said circuit.

6. A microphone relay device comprising a microphone and suspended primary and secondary coils rotatable against each other, arms carried by said coils, the microphone 20 being subjected to pressure from said coils, a circuit including said secondary coil, a battery and said microphone, and a hearing device connected across to said circuit.

In testimony whereof I have hereunto set 25 my hand in presence of two subscribing witnesses.

CURT STILLE.
